UNITED STATES PATENT OFFICE.

IRVING FLORMAN, OF NEW YORK, N. Y.

AUTOMOBILE RADIATOR CAP.

Application filed November 19, 1924. Serial No. 750,820.

This invention relates to automobile radiator caps, and has particular reference to radiator caps of the non-removable type.

It has been proposed heretofore to provide 5 non-removable radiator caps adapted to be permanently screwed into the nipple of the radiator opening of an automobile so as to prevent any unauthorized removal thereof, and which are constructed to permit the filling 10 of the radiator in a well known manner. The chief disadvantage in the use of a radiator cap of the type referred to lies in the fact that it is necessary for the retail dealer to keep in stock a large number thereof of varying 15 diameters in order to fit the different makes of automobiles, each of which is provided with a different size thread and filling opening for the radiator.

A general object of the present invention 20 resides in the provision of a non-removable radiator cap which can be applied with equal facility to any type of radiator.

A further object of the invention resides 25 in a non-removable radiator cap in which the ordinary radiator cap with which all automobiles are furnished is utilized, thereby preventing the scrapping of the latter as necessary in the application of caps of this type heretofore in use.

30 A further feature of the invention consists in a novel non-removable radiator cap which is simple in construction, readily applicable to any make of automobile, durable in use, and comparatively cheap to manufacture.

These and other important features of this 35 invention will appear from the following detailed description read in connection with the accompanying drawings, and will be particularly pointed out in the appended 40 claims.

In the drawings:

Figure 1 is a side elevation of a preferred 45 form of the invention;

Figure 2 is a rear elevation thereof;

Figure 3 is a vertical section of the casing, the position assumed by the top in open position being shown in dotted lines; and

Figure 4 is a front elevation of the body 50 of the casing.

Referring more particularly to the drawings, the usual radiator cap for closing the filling opening of an automobile radiator is indicated at 2. The cap 2 is ordinarily provided with an opening 4 adapted to receive 55 a temperature indicator, mascot, or similar

device therein. The construction of the cap is well known, and, since it does not constitute an essential part of the present invention, will not be described in detail herein.

The reference character 6 designates a hollow cylindrical body or casing comprising a wall portion 8 and a bottom 10. The underside of the bottom is slightly concave, as illustrated in Figure 3, to conform with the top of the radiator cap 2, upon which the casing is mounted. The bottom 10 of the casing is formed with a central opening 12 which communicates with a centrally arranged tube 14 formed integral with the bottom of the casing. The tube 14 is screw-threaded and adapted to extend through the opening 4 of the cap 2. A washer 16 and lock nut 18 serve to securely retain the casing upon the cap 2 in a manner clearly understood.

The casing 6 is provided with a rearwardly and upwardly extending lug 20 which is bifurcated at its upper end to provide spaced bearing arms 22 for a purpose hereinafter described. The casing 6 is provided with a cover or top 24 having a peripheral flange 26 adapted to snugly fit around the upper edge of the casing. The top 24 is provided with a gasket or washer 28 of rubber or other suitable material which serves to hermetically seal the casing when the top is in closed position.

The top 24 is formed with an integral lug 30 having an elongated slot 32 therein, the said lug being adapted to extend between the bearing arm 22 previously mentioned. A stud or bolt 33 extends through the arms 22 and the elongated slot in the lug 30 to afford a pivotal mounting for the top. The lug 30 is also formed with an extension or tail 34 adapted to engage the side of the casing to limit the pivotal movement of the top when the latter is opened.

The top 24 is provided with an upstanding boss 36 adapted to support a temperature indicator, mascot, or similar device 38. The temperature indicator is of standard and well known construction, and need not be described in detail. As illustrated, the temperature indicator is provided with a pedestal 40 adapted to seat upon the boss 36 and has a reduced extension 42 extending through the boss, the top 24, and the rubber gasket 28, suitable holes being provided in the top and gasket for this purpose. cap, said tubular member forming a passageway between the casing and the radiator, a hinged top on said casing provided with an opening therein to receive a portion of a 5 temperature indicator, mascot or similar device, means on the inside of the top for securing the temperature indicator, mascot or similar device to the top of the casing, and releasable means for retaining the top of 10 the casing in closed position.

6. A filling device for automobile radiators adapted to be attached to the usual radiator cap which has been permanently fixed to the radiator neck, said filling device 15 comprising a casing adapted to seat on the

radiator cap, a tubular member formed upon the bottom of the casing adapted to extend through an opening in the radiator cap, said tubular member forming a passageway between the casing and the radiator, means on 20 the interior of the radiator cap engaging said tubular member for securing the casing to the cap, a hinged top on said casing adapted to carry a temperature indicator, mascot or similar device, means for arrest- 25 ing the movement of the top towards open position, and means for releasably retaining the top in its closed position.

In testimony whereof I affix my signature.
IRVING FLORMAN.
